UNITED STATES PATENT OFFICE.

JOHN N. SELVIG, OF CHICAGO, ILLINOIS, ASSIGNOR TO UNIVERSAL FIBER COMPANY, A CORPORATION OF MAINE.

FEEDING MECHANISM FOR FIBER-TREATING MACHINES.

No. 928,223.

Specification of Letters Patent.

Patented July 13, 1909.

Application filed July 27, 1907. Serial No. 385,783.

To all whom it may concern:

Be it known that I, JOHN N. SELVIG, a citizen of Norway, residing in the city of Chicago, county of Cook, and State of Illinois, have invented certain new and useful Improvements in Feeding Mechanism for Fiber-Treating Machines.

This invention relates to that class of feeding mechanisms comprising flexible feed belts adapted to engage the fibrous material or stalks to be fed into position to be operated upon by breaking, cleaning or scutching mechanism, and having chain and guide mechanism for supporting, guiding, strengthening or operating the belt mechanism.

The principal object of the invention is to provide a simple, economical and efficient feeding mechanism for machines for breaking, scutching, cleaning or treating hemp, flax, ramie, jute, sisal or other fibrous stalks or material.

A further object of the invention is to provide a feed belt or belts of preferably compressible material with suitable improved means for supporting, guiding and operating the same and adapted to minimize the stretching of and reduce the strains upon the belts and hold them in efficient operative engagement with the fibrous material to be fed thereby.

Further objects are to provide preferably compressible or elastic flexible feeding belts with supporting, guiding and belt operating chains mounted upon sprocket wheels and in engagement with the belts and so constructed that all parts of the chains and belts which are in contact with each other will move in unison or at the same speed throughout their entire path of movement, both around the wheels upon which the chains are mounted and from wheel to wheel thereby reducing the stretching of the belts, relieving them of much of the strain to which they would otherwise be subjected, minimizing the friction and wear upon the parts and increasing their efficiency and durability in operation; to provide a feeding-chain so constructed that it is adapted to support a feeding-belt of compressible or elastic material in such position that the

pitch line or line between the inner compressed side or portion of the belt and its outer tension or stretched side or portion will be in line with and move at all times at the same speed with the articulations or points of pivotal connections of the links of the chain when mounted upon sprocket wheels; to enable this to be accomplished in such a manner that the adjacent portions of the upper and lower feeding-belts may move in a straight line at the same speed and with the pitch lines of the belts the same distance from the centers of the supporting sprocket wheels as the points of pivotal connections between the links of the chain, the inner sides of the belts being outside of the pitch line of the sprocket wheels and preferably outside of the peripheral points of the sprocket-wheel teeth, and to provide the necessary rigidity and strength or a suitable backing and guide for the portions of the belts between which the material to be fed is held during the feeding operation.

Other and further objects of the invention will appear from an examination of the drawings and the following description and claims.

The invention consists in the features, combinations and details of construction hereinafter described and claimed.

In the accompanying drawings Figure 1 is a view in side elevation of a feeding mechanism constructed in accordance with my improvements; Fig. 2, a plan view of the mechanism shown in Fig. 1, and showing a portion of a break-bar and rotary beater of a hemp or fiber breaking and scutching machine in position to operate upon material while being fed by the feeding mechanism, and also showing the rear portion of the main feed chain; Fig. 3 a detail sectional view showing the adjacent laps of the upper and lower feed-belts and chains and the position of the oblique breaker bar and rotary beater as they would appear on line 2 of Fig. 1, and line 3^a of Fig. 2, looking in the direction of the arrow; Fig. 4, an enlarged detail plan view of a portion of a chain constructed in accordance with my improvements and mounted upon a sprocket-wheel; Fig. 5, a view in side elevation of the parts

shown in Fig. 4 and, Fig. 6, an enlarged view in detail in cross-section, the lower portion showing the chain illustrated in Fig. 4, as it would appear taken on line 6 of said figure, with the flexible belt in position thereon outside of the sprocket-wheel teeth, and the upper part showing the lower lap of the upper belt and chain in cross-section.

In constructing a feeding mechanism in accordance with my improvements supporting sprocket-wheels *a* mounted upon shafts *b*. The shafts are preferably in fixed relation to the sprocket wheels and are rotatably mounted in supporting and chain and belt guiding-members *c*. Said supporting and guiding members are mounted upon suitable portions *d*, *e*, *f*, *g*, *h*, *i*, and *j* of the framework of a hemp and flax or other fiber breaking, scutching and cleaning machine having fiber treating mechanism adapted to break, scutch or clean the stalks of fibrous material as they are fed and held in position to be operated upon.

The feeding mechanism here shown is particularly adapted to be used in connection with machines for breaking, scutching or cleaning hemp, flax or similar fibrous stalks or material wherein the stalks are to be fed transversely with relation to their length and obliquely with relation to the break-bars, rotary beaters or fiber-treating mechanism, and is intended to receive the partially scutched or cleaned material from the initial or main feeding-mechanism during the passage of the material through the machine and by grasping the scutched and cleaned portion of the material to feed the remaining unbroken, unscutched or partially broken portion of the stalks into position to be broken scutched and cleaned. The difficulties to be overcome in properly holding and feeding such partially broken and cleaned material is well known to those skilled in the art, and I have here shown only such portions of a hemp or flax breaking and scutching machine as is necessary or desirable to enable those skilled in the art to understand the nature of this invention, its construction, purposes, mode of operation and advantages.

The supporting and guiding member *c* above mentioned are mounted preferably parallel with the rear portion of the main feed-chain *k* and alongside of and in oblique relation to the rotary beater and its blades *l* and break-bar *m* which are in position to break and scutch and clean the fibrous material while it is being fed thereto by the feeding mechanism between the said guides— as indicated in Figs. 2 and 3. The beater blades *l* are mounted upon the radiating arms or spokes *n* of wheels or rotatable frames forming rotary beaters which may be of any ordinary and well known type. In short the breaking, scutching, cleaning or

treating mechanism a portion of which is here shown consisting of beater blades *l*, and break-bar *m* is well known in the art and may be of any ordinary and well known or desired type and it is therefore not deemed necessary or desirable to illustrate or describe the same herein in detail. The supporting and guiding members *c*, being mounted in oblique relation to the fiber treating or breaking and scutching mechanism are adapted to determine the direction of movement of the fibrous material and hold the moving parts of the feeding mechanism in place. The side members *o* of both upper and lower guides are mounted in parallel relation on opposite sides of the sprocket wheels to be supported thereby, and are connected by inner members *p* which are secured thereto by means of angle irons *q*. These inner or web portions *p* of the guides are provided with openings *r* therethrough for admitting the sprocket wheels. The inner horizontal web portion *p* of the upper guide extends from wheel to wheel in such position that its bottom face is in line with the lowermost peripheral portions of the wheels and the horizontal web portion of the lower guide has its upper face in line with the uppermost peripheral face of the lower sprocket wheels, both of said horizontal portions being rigid and one above the other, parallel, and with a space therebetween. Mounted in each of these guides between the horizontal inner or web portions and also between the upright side members *o* are supporting and feeding chains each preferably of identical construction except as to width and formed of links constructed and connected as shown in Figs. 4, 5, and 6. These links consist of side members or portions *s* connected by transverse members or integral portions *t* and *u*, the lower faces of which are adapted to rest upon the peripheral face *v* of the sprocket wheel or wheels and to slide upon the faces of the horizontal members of the guides respectively. Designating the side of the chain the links, and the belts *y* which is toward the center of the wheels around which they pass as the inner side or bottom side, and the opposite side as the outer or top side, the upper or outer faces of the transverse portions *t* and *u* are inside of or below the pivots *z* which form the articulate connections or pivotal connections between the links. Said upper or outer faces of the transverse portions of the links are outside of the pitch line of the sprocket wheels or flush with or above or outside of the outer peripheral ends of the sprocket teeth *3*. It will also be noted that the points of articulate or pivotal connections between the links of the chains are outside of and above the outer ends or peripheral portions of the sprocket teeth and outside of and above the

pitch line of the sprocket wheel as well as outside of and above the inner side of the belt.

The inner side of the belts rest upon the outer faces of the transverse portions *t* and *u* of the links of the chains and are inside of and below the points of pivotal connection or articulations of the links of the chains, the outer faces of said belts *y* being outside of and above the pivotal points or pitch line of the chain. In other words, the belts are formed of an inner portion of relatively strong and inelastic but flexible fabric or webbing and their outer portions are provided with interlapping corrugated or ribbed portions *z* preferably integral with the inner webbing and made of guttapercha or india rubber molded with the webbing and forming a compressible elastic outer portion adapted to grasp and securely hold the fibrous material or stalks between the upper and lower belts, and the belts thus formed have all of their inner compression portion inside of or below the pivotal connections of the chain links and their outer portion which stretches as it goes around the wheels is all outside of or above the articulations or pivotal connections between the links of the chains upon which the belts are mounted. The pitch line of the belt or the line between its outer stretching portion and its inner compression portion is thus on the same plane or in line with the line of articulations or pivotal connections between the links of the chain, and the pitch-line or line of bending of the belt is in line with and corresponds with the pitch-line or line of bending or articulation or pivots of the chain. The outside of the belt thus has its tendency to stretch reduced to a minimum and the pitch lines or lines of bending of the belts and chains being the same there is no movement of the belts longitudinally of the chains as they pass around the pulleys, belts and chains both move at their bending points at the same rate of speed throughout their length, and the surfaces of the chains and belts where they are in engagement with each other are thus enabled to remain in substantially fixed relation, reducing the friction therebetween to a minimum. A rigid backing or support for holding the belts in contact with the material to be operated upon is enabled to accomplish its objects or perform its functions without being in sliding contact with the more compressible belts so that the wear is upon the more durable chain and not upon the belts and at the same time positive action of the belts and of the entire feeding mechanism is secured.

It will be noted that the links of the chain above described are adapted to be stamped each in one integral piece with the side portions bent up, or they may be molded or cast of any desired metal. While the feed-

ing device is adapted to feed stalks transversely with relation to their length its use is not limited to this, and the direction in which the material is fed with relation to the fiber treating mechanism may be varied as desired. 70

I claim:

1. In a mechanism of the class described, the combination of a chain having pivotally connected links, and a belt mounted upon the chain, having its inner face on one side of the pivotal points of the chain and its outer face extending outward on the opposite side of said pivotal points. 75

2. In a mechanism of the class described, the combination of a chain having pivotally connected links, a belt mounted upon the chain having its inner side on one side of the pivotal centers of the chain and its outer side on the opposite side of said pivotal 80 centers, and a guide in engagement with the chain.

3. In a mechanism of the class described, the combination of a chain having pivotally connected links, and a belt in operative engagement with the chain having its inner face on one side of the pivotal centers of the chain and its outer face extending outward beyond the opposite side of the chain, the chain being provided with transverse portions entirely on one side of pivotal centers 90 of the chain and forming a support for the inner side of the belt. 95

4. In a mechanism of the class described, the combination of a chain having pivotally connected links, a belt mounted upon the chain, having its inner face extending on one side of the pivotal centers of the chain and its outer face extending outward on the opposite side of said pivotal centers, a second belt extending adjacent to and parallel with a portion of said chain-supported belt, and supporting wheels upon which said chain and belt mechanism is mounted. 100

5. In a mechanism of the class described, the combination of a pair of chains each having pivotally connected links, a belt mounted upon each of said chains each of said belts having its inner face extending on one side of the pivotal centers of the 110 chain on which it is mounted and its outer face extending outward on the opposite side of said pivotal centers, said belts having adjacent parallel portions movable in parallel directions, and means for supporting said 115 belts and chains. 120

6. In a mechanism of the class described, the combination of a pair of chains each having pivotally connected links, and a belt mounted upon each of said chains, each of said belts having its inner face extending on one side of the pivotal centers of the chain on which it is mounted and its outer face extending outward on the opposite side of said pivotal centers, said belts and chains 125 130

- having adjacent parallel portions movable in parallel directions, and the adjacent parallel portions of the belts being between the parallel adjacent portions of the chains.
5. In a mechanism of the class described, the combination of a pair of chains each having pivotally connected links, a belt mounted upon each of said chains, each of said belts having an inner side extending on one side 10 of the pivotal centers of the chain upon which it is mounted and its outer face extending outward on the opposite side of said pivotal centers, said belts and chains having adjacent parallel portions movable in parallel directions and adapted to clamp material between the belts to be fed thereby, and guides in engagement with the chains adapted to guide the chains and thereby the adjacent portions of the belts.
15. In a mechanism of the class described, the combination of a pair of chains each having pivotally connected links, and wheel engaging side portions, a belt mounted upon each of said chains having its inner side extending inward beyond the pivotal centers 20 of the links of the chains in the direction of the wheel engaging sides thereof and the opposite side of each of said belts extending outward beyond the opposite sides of the 25 chains upon which they are mounted, the belts having adjacent parallel portions, adapted to clamp material therebetween to be fed thereby, and sprocket wheels having teeth in engagement with the chains and 30 encircled by the inner sides of the belts.
35. In a mechanism of the class described, the combination of a break-bar, beater mechanism mounted adjacent thereto, a pair of chains each having pivotally connected links, 40 and a belt mounted upon each of said chains, each of said belts having an inner side extending upon one side of the pivotal centers of the links of the chain upon which it is mounted and its outer face extending outward upon the opposite side of said pivotal centers, said belts and chains having adjacent parallel portions movable in parallel 45 directions toward the break-bar and beater mechanism and adapted to clamp material between the belts to be fed thereby.
50. In a mechanism of the class described, the combination of beater mechanism, a pair of chains each having pivotally connected links, and a belt mounted upon each of said 55 chains, said belts having adjacent parallel portions movable in parallel directions and in oblique relation to the beater mechanism and adapted to hold material between said belt portions to be fed to the beater mechanism.
60. In a mechanism of the class described, the combination of beater mechanism, a pair of chains each having pivotally connected links, a belt mounted upon each of said chains said belts having adjacent parallel 65 portions movable in parallel directions toward and at an angle with relation to the beater mechanism, stationary guiding mechanism in engagement with the chains, and sprocket wheels upon which the chains are 70 mounted.
75. In a mechanism of the class described, the combination of beater mechanism, a chain having pivotally connected links, a belt mounted upon said chain and having its inner side extending upon the inner side of the pivotal centers of the links of the chain and forming a feeding lap which extends and is movable toward and at an angle with relation to the beater mechanism, means for 80 guiding the chain and thereby the feeding lap of the belt, and means for holding fibrous material in engagement with the feeding lap of the belt to be fed thereby.
85. In a mechanism of the class described, a chain having pivotally connected links each provided with side portions forming a space therebetween which extends uninterruptedly above, below and between the pivotal centers of the chain throughout its 90 entire length, and a belt mounted in the space formed between the side portions of the chain.
95. In a machine of the class described, a chain having pivotally connected links each provided with side portions and integral transverse portions connecting the side portions on one side only of the pivotal centers of the links of the chain and forming a space between the side portions of the links of the chain which extends uninterruptedly throughout the entire length of the chain above, below and between the pivotal centers of the links for admitting a belt to be mounted in the chain.
100. In a machine of the class described, the combination of a chain having pivotally connected links, and a belt mounted upon the chain and having its pitch line or line of bending in alinement or in the same plane 105 with the pivotal centers of the links.
110. In a machine of the class described, the combination of a chain having pivotally connected links, sprocket wheels mounted in toothed engagement with the chain, the pivotal connections between the links of the chain being outward beyond the outer peripheral ends of the sprocket teeth, and a belt mounted upon the chain and having its pitch line or line of bending in alinement 115 with the pivotal centers of the links of the chain.
120. In a machine of the class described, the combination of a chain having pivotally connected links, sprocket wheels mounted in toothed engagement with the chain, and a belt mounted upon the chain and extending between the ends of the pivots and on oppo-

site sides of the pivotal centers formed thereby.

18. In a machine of the class described, the combination of an endless chain movably mounted and having a straight and curved portions, and a belt mounted upon and parallel with the chain and encircling the

curved portions thereof, the belt and chain being adapted to move together at the same rate of speed throughout their entire length. 10
